NONSLIP LEATHER SOLE

Charlotte T. Johnson, Chicago, Ill.

Application March 5, 1942, Serial No. 433,413

2 Claims. (Cl. 36—59)

My invention, which relates to the art of shoe making, contemplates and provides a leather out-sole having a relatively smooth upper surface and a non-slip walkway-engaging or tread surface in the form of a multiplicity of grippers which are derived from and integral with the leather sole itself.

The non-slip leather sole of my present invention is particularly advantageous when used on infants' shoes, but its use is not to be regarded as necessarily so limited.

One of the principal objects of my invention is to provide leather shoe soles with integral walkway grippers that are particularly effective in preventing forward slippage of the feet from under a wearer of shoes equipped with such soles—this being a very important consideration when the soles are applied to infants' shoes.

Another object of my invention is to provide a relatively thin leather shoe sole with effective walkway grippers which cause no discomfort to a shoe wearer's foot bearing either directly, or through a thin stocking, upon the upper surface of the sole structure.

Another object of my invention is to provide a relatively thin leather out-sole with walkway grippers which cushion the sole and thus render it more comfortable to wear than it would be if such grippers were not present.

Another object of my invention is to provide a leather shoe sole with walkway grippers in such manner that the ability of the sole naturally to flex with a shoe wearer's foot is enhanced, rather than diminished, as would be the case were the grippers in the form of hobs, cleats, pads or plates embedded in or attached to the sole.

And still another object of my invention is to provide a novel method of making a practical non-slip leather out-sole, which may be carried out with the aid of inexpensive and economically operable equipment.

These and other features, objects and advantages of my invention will appear from the following description, wherein reference is made to the accompanying sheet of drawings, in which

Fig. 1 is a side elevational view of an infant's shoe embodying the sole of the present invention, drawn on an enlarged scale to emphasize the predominant features of the invention;

Fig. 2 is a bottom plan view of such sole;

Fig. 3 is a greatly enlarged sectional detail view taken in the plane of line 3—3 of Fig. 2 and shows more or less schematically the results

of compression of the leather in the formation of the non-slip walkway grippers;

Fig. 4 is a diagrammatic perspective illustrating the principal elements of the equipment wherewith I prefer to provide my improved shoe soles with their walkway grippers; and

Fig. 5 is a schematic diagram illustrating how a plurality of leather out-sole-receiving plates or trays may be mounted on an endless carrier passing under a vertically reciprocating die which acts progressively a multiplicity of times upon each leather out-sole passing therebeneath.

Having more particular reference to the drawing, an infant's shoe 10 embodying the features of the invention, has been selected as the illustrated example because of the perhaps greater advantages resulting from the use of my invention in shoes of this class as compared with other classes of footwear. Due to the relatively undeveloped condition of their muscles, infants as a class are notoriously unsteady on their feet, and therefore any slipping of the walkway-engaging surface of the shoe soles during walking has a far greater unsteading influence on infants than upon more mature individuals.

It should be remembered, however, that although infants' shoes offer a large and very important field for use for the invention, the improved results of the invention are of very substantial value when applied to other types of shoe. For instance, old folks will find grateful relief from worry over the danger of falling due to slipping where their shoes are provided with non-slip out-soles embodying the present invention. Certain sport shoes, such as bowling shoes, are improved by the use of my invention. In fact, the novel non-slip feature of the invention is advantageously applicable to all shoes which employ a leather out-sole, and which should be as free as practicable from danger of slipping on the walkway, without the use of hobs, cleats, pads, spike plates, or the like.

The shoe 10 includes the usual or preferred features of shoe construction such as an upper 11, a welt 12, a heel-wedge or insert 13, and a leather out-sole 14 which is secured to the welt 12 by stitching 14a. Since this is an infant's shoe, the walkway face of the sole 14 covers both the ball and the heel portions of the shoe in a common plane.

According to the invention, the out-sole 14 is cut to shape in a single piece from suitable sole leather and has the bottom or walkway-engaging surface thereof formed with an arrangement of linear prominences providing non-

slip treads or grippers 15. As shown in Figs. 1 and 2, the grippers 15 are of uniform size and shape and uniformly cover the entire walkway-engaging surface.

Each of the grippers 15 extend entirely across the sole from edge to edge and lies at right angles to the direction of the main slippage to be prevented, that is, longitudinally of the shoe. In cross-section, each gripper preferably has a substantially ratchet-tooth shape, that is, is formed with two faces angularly related to each other and respectively angularly related to the original face plane, identified by P in Fig. 3, of the leather surface in which they are formed. One of such gripper surfaces, identified by the numeral 16, extends at a quite abrupt angle, preferably about ninety degrees, to the plane P, while the other surface, identified by the numeral 17, extends at a relatively gently sloping angle, of preferably between five to twenty degrees relative to such plane. The gripper surfaces 16 and 17 join at a relatively sharp prominence or ridge edge 18.

In the preferred arrangement, the gently sloping surface 17 of each gripper extends from the edge 18 to convergence with the foot of the abrupt surface 16 of the immediately adjoining gripper 15. The gripper surfaces 16 preferably face forwardly towards the toe end of the sole 14, thus providing a continuous, uniform series of abrupt shoulders facing in the forward direction in which slipping most generally occurs with ordinary leather soled shoes. Although in the preferred form, as shown, the grippers 15 are preferably of a normal width of about $\frac{1}{8}$ " and in juxtaposed relation, it will be clear that the size of the grippers may be varied and they may be spaced apart or disposed in various arrangements to meet special preferences or requirements and conditions.

In a preferred method of providing the leather out-sole 14 with the grippers 15, the walkway face of the sole leather is subjected to shallow shearing along spaced lines to provide the abrupt surfaces 16, and also to compression and compacting in limited elongated areas adjoining the shear lines to depress the leather and form the slanting surfaces 17 of the grippers. All of this is preferably done after the sole leather has been at least rough-cut into the desired shoe-sole shape but before the sole has been attached to the shoe.

At the time the sole leather is subjected to such shearing and compression, it may be dry or moistened with a suitable liquid, warm or cold, and the pressure may be accompanied by heat, all depending upon the precise results desired as to the prominence and permanence of the grippers and also depending upon the kind and quality of leather being used. Moreover, the grippers 15 may be formed either on the smooth or hair side of the leather, or on the flesh or rough side of the leather, depending upon the use or effect intended. Before or after the gripper-producing treatment, the walkway-engaging face of the sole may, if desired, be treated with a suitable coating or impregnating substance.

In carrying out the method, care should usually be exercised to keep the back face of the leather, that is, the face opposite the walkway-engaging face of the sole 14, in as nearly as practicable its original flat state, especially where such flat surface is itself to provide the insole surface of the shoe or is to be covered 75

with only a thin and not self-sustaining insole. For this purpose, the sole leather should be backed up with a smooth and unyielding surface when the compacting pressure is applied to the walkway surface in forming the grippers 15.

The compacting pressure is applied with greatest force immediately in front of the abrupt surface shoulder 16 of the grippers and to progressively diminishing extent up the slopes of the surfaces 17. As indicated at C in Fig. 3, this causes the fibers of the leather in the region immediately adjacent the converging foot edges of the gripper surfaces 16 and 17 and inwardly 15 of the base areas of the sloping surfaces 17, to be most compacted and dense, with corresponding decrease in density as the gripper edges 18 are approached. The outer edge zones of the grippers are uncompacted. Since the compression force is then concentrated along spaced lines, there appears to be a slight displacement of the leather fibers toward and into the un-compressed edge zones of the grippers, resulting in a slight puffing up and outward extension of the edges 18 beyond the original face plane P of the leather. This has the advantage of softening the grippers 15 and endowing them with a certain springiness, which cushions the sole 14 and gives the wearer greater walking comfort.

30 The compacted zones C afford substantial bridges across the gaps or hollows between the grippers 15 and act to sustain and keep in a uniform plane the back face of the sole 14 so that the grippers will not be felt by the wearer's foot.

35 By preference, each of the grippers 15 is formed separately and successively, in an order starting the formation of the grippers at the 40 toe end of the leather sole 14 and completing at or adjacent the heel end. One way in which I accomplish this is by advancing the sole step by step, by gripper width increments, between forming means such as the equipment shown 45 schematically in Figs. 4 and 5. This comprises a substantially non-bendable metal plate or tray 20 for supporting the sole under a die 21 which is carried by a ram 22 for vertical reciprocation into and out of pressure engagement with the upwardly facing walkway-engaging surface of the sole in timed relation to gripper-width incremental advancing movements of the tray 20.

50 The leather sole 14 is held centered upon the tray 20 within the confines of a shallow flat bottom depression 23 having the same outline as the sole and which is of a uniform depth only a small fraction as deep as the thickness of the leather. Thus, when the sole is fully received in the depression 23, the major thickness of the leather projects above the flat upper surface of the tray sufficiently to receive fully therein a combined shear member and pressure rib 24 on the die 21, while yet affording ample clearance between the edge of the pressure rib and the surface of the tray at the bottom of the pressure stroke, even when the die is operating upon the narrower parts of the sole.

55 The pressure rib 24 is, of course, long enough to extend entirely across the sole 14 and is the substantial counterpart of one of the grippers 15, having a relatively sharp lower edge 25 at which the abrupt and sloping surfaces of the rib meet.

60 On initial contact with the surface of the sole leather, the sharp edge 25 acts to cut into such

surface which, being relatively yieldable, will to some extent resist the cutting and tend to give before the oncoming die. However, the unbroken surface of the leather has a substantial surface tension (the tenacity of which depends upon the kind or lack of finish upon the surface) which counteracts the yielding and allows the edge 25 to penetrate the surface and shear down cleanly into the leather along the abrupt surface of the rib to form one of the abrupt gripper surfaces 16. At the same time the sloping surface of the pressure rib 24 compresses the leather therebeneath to form the sloping surface 17 of another of the grippers 15. Thus, by advancing the leather sole as shown in Fig. 4, so that the rib edge 25 always attacks an unbroken surface area of the leather, there is assurance of a clean severance of the abrupt gripper faces 16. Coincidentally, there is, of course, no surface tension of the leather at the edge 18 of the gripper being formed which might tend to resist the slight displacement and puffing up of the edge zone of the gripper as the sloping surface of the pressure rib bears down against the long, narrow area of leather therebeneath and just in advance of the previously cut abrupt gripper surface 16. The pressure stroke of the die is adjusted to stop short of compression of the edge 18 of the gripper.

In order to operate the apparatus continuously, a preferred arrangement consists in having a continuous series of the trays 20 traveling under the die 21 so that the die can operate on successive leather soles substantially without interruption. As shown in Fig. 5, the trays are carried in endless belt fashion by a sprocket chain structure 26 running over spaced sprocket wheels 27. Under the die head is a bolster 28 for backing up the tray 20 which at any time is receiving the force of the die stroke. As shown in Fig. 4, the trays 20 may be formed for alternately receiving right and left shoe soles so that during a given period of operation an equal number of right and left soles can be treated for the desired number of complete pairs of shoes. At the discharge end of the machine a receiver 29 may be provided to receive and stack the treated soles as they drop off or are dislodged from the successive trays at the beginning of the return run of the tray belt. It is to be understood, of course, that the apparatus and the procedural steps illustrated and described may be varied to a considerable extent, and such details of the mechanism as are not shown are of conventional construction and operation and can readily be supplied by any mechanic.

It is noteworthy that a wearer of a shoe equipped with my improved leather sole is not conscious of any difference in the sole aside from its non-slip characteristics, and that it is possessed of unusual walking flexibility especially when new. The grippers 15 being relatively shallow, narrow, closely spaced, and cushioned, are not perceptible to the wearer's foot—that is, there is no "corrugated" sensation to the foot. If there is any difference in sensation it is rather that of an unusual softness or cushioning arising both from the greater walking flexibility of the sole and from the softness of the walkway contacting portions of the grippers 15. In addition to the softness arising from the somewhat puffed or extended condition of the grippers 15, a certain additional softness is also probably due to the substantial elimination of surface tension by the cutting of the leather surface.

Apparently the relative softness of the walkway contacting portions of the grippers 15 is 75

also an important factor, supplementing the abrupt gripper shoulders 16, in the non-slip function of the treated sole. As a result of this softness, not only do the grippers enter into better engagement with the walkway to resist slipping forwardly, but to some extent also to resist side-wise slipping.

Moreover, since the walkway-engaging face of the sole is broken up into the relatively independent areas of the grippers 15, and the face is relieved of surface tension tending to retain the face taut, such face is not subject to wearing down to a slick finish at least in those areas receiving the greatest pressure from the foot in walking. This eliminates a condition which increases the tendency toward slipping with ordinary leather soles, and particularly the soles of infants' shoes.

Although a leather shoe sole treated according to my invention is more flexible in the longitudinal or walking direction, there is no weakening of the leather in a transverse direction but actually a strengthening thereof due to the compacting of the fibers along unbroken transverse lines. Therefore the wearer's foot is firmly supported against unnatural in- or out-turning or twisting but is supported and guided in a normal forward direction. This is of particular orthopedic value for infants since it counteracts abnormal tendencies such as toeing-out or toeing-in in walking, but guides and controls proper walking so as to assist in the proper development of the foot muscles.

While I have illustrated and described a preferred embodiment of my invention, many modifications may be made without departing from the spirit of the invention, and I do not wish to be limited to the precise details set forth, but desire to avail myself of all changes within the scope of the appended claims.

Having thus described my invention, what I claim as new and desire to secure by Letters Patent of the United States is:

1. A leather outsole for a shoe having on the walkway-engaging face thereof a plurality of non-slipping grippers formed integrally with and derived directly from the leather itself, each of the grippers comprising a pair of divergently related surfaces, one of said surfaces comprising the contiguous original surface area of the walkway-engaging face of the sole, the other of said gripper surfaces comprising a cleanly sheared raw leather plane area extending angularly inwardly from the original walkway-engaging face plane and facing toward the toe end of the sole, the said one surface of each of the grippers slanting heelward inwardly toward the base of the adjoining sheared raw leather surface of the heelward adjacent gripper to expose such raw leather surface for non-slip gripping action in the use of the sole, the material of each gripper inwardly of the base region of said one surface and the contiguous unsheared portion of the sole leather being permanently compacted to substantially greater density than the normal density of the leather, and the leather contiguous to the ridge portions and to the raw leather surfaces of the grippers being of a density approximately the same as the density normal in the leather prior to formation of the grippers.

2. A leather outsole as defined in claim 1, in which the ridges of the grippers are upset to project outwardly beyond the original walkway-engaging face plane of the sole.
